UNITED STATES PATENT OFFICE.

HARRY SILBERMAN, OF NEW YORK, N. Y.

DESIGN FOR A TEXTILE FABRIC OR THE LIKE.

Application filed December 21, 1926. Serial No. 20,106. Term of patent 3½ years.

To all whom it may concern:

Be it known that I, HARRY SILBERMAN, a citizen of the United States, and a resident of the city of New York, borough of Manhattan, in the county and State of New York, have invented a new, original, and ornamental Design for Textile Fabrics or the like, of which the following is a specification, reference being had to the accompanying drawing, forming part thereof.

The figure is a plan view of a textile fabric, showing my new design.

I claim:

The ornamental design for a textile fabric or the like, as shown.

HARRY SILBERMAN.
